LOCK JOINT SHINGLE

George F. Waske, Parnell, Mo.

Application July 11, 1956, Serial No. 597,177

4 Claims. (Cl. 108—17)

This invention relates to a covering for buildings or the like and more particularly to a shingle construction which may be utilized for either the side walls or roofs of the building.

The present invention is an improvement over my application, Serial No. 562,677, filed February 1, 1956.

It is the principal object of the present invention to provide a shingle or covering for building structures made from light metal such as aluminum, tin, or the like, or a plastic material as I do not wish to be limited to any particular kind of material or to any particular size or shape of plate. In press forming materials various designs of semi-circular forms may be used in my system of application, the provision of the centering tabs and nail tabs being important features of my invention.

Other objects of the present invention are to provide a covering from sheets of material having fold lines or adapted to be folded on particular lines or press formed into these shapes as in use of such materials as plastics, fiber glass and forming said centering tabs and nail tabs, providing a centering tab and nail tabs, the nail tabs being so situated on the sheet for nailing to the building structure and the next succeeding piece of material be placed thereover to cover the nail structure; to provide a structure whereby the succeeding layers of material may be placed over the previous sheets to close the spaces between the sheets to prevent moisture from entering or passing through the sheets and thus closing the vents provided in the tabs of my previous application; to provide a shingle construction made from a flat sheet of material and folded whereby each shingle may be interlocked into one another and nailed to the roof of the building structures through tabs extending outwardly from the body of the shingle providing a nailing place beyond the folded portions of the shingle; to provide a covering of diamond or rhomboid shaped sheets wherein two points will be in vertical position, the other two will be in horizontal position when the shingles are fastened to the roof or wall structure; to provide a shingle or sheet of material or parallelogram shape having right congruent angles when placed on the wall structure; and to provide a device of this character simple and economical to manufacture.

In accomplishing these and other objects of the invention, I have provided improved details of structure the preferred forms of which are illustrated in the accompanying drawings, wherein:

Fig. 1 is a fragmentary top plan view of my shingle construction shown on a building structure.

Fig. 2 is a top plan view of one sheet of material folded to form interlocking side edges for the shingle.

Fig. 3 is a bottom plan view of the sheet shown in Fig. 2.

Fig. 4 is a top plan view of the sheet showing the fold lines in dotted lines and the slots for forming the tabs for nailing of the shingles to a roof structure.

Fig. 5 is a fragmentary enlarged view of one corner of the sheet partly folded or partly formed.

2

Fig. 6 is a fragmentary enlarged view of the upper corner of the sheet shown in Fig. 4 and shown in partly formed position.

Fig. 7 is a cross sectional view showing the locking 5 side members of the shingle.

Fig. 8 is a cross sectional view taken on a line 8—8, Fig. 2.

Fig. 9 is a view similar to Fig. 5 but showing a different way of folding the corner nailing tabs.

Fig. 10 is a top plan view of a modified form of the structure showing a diamond shaped sheet of material.

Fig. 11 is a fragmentary enlarged view of the fold of the upper corner of Fig. 10.

Fig. 12 is a fragmentary enlarged view of the fold of 15 the right hand nailing tab shown in Fig. 10.

Fig. 13 is a view similar to Fig. 12 with the nailing tab folded in position.

Fig. 14 is a top plan view of a sheet of material showing fold lines in dotted position for a parallelogram 20 shaped structure.

Fig. 15 is a fragmentary view showing the tab in the upper right hand corner of Fig. 14 in partly folded position.

Fig. 16 is a similar view of the lower right hand corner 25 showing the nailing tab of Fig. 14 in partly formed condition.

Fig. 17 is a view similar to Fig. 16 with the nailing tab in completely folded position.

Referring more in detail to the drawings:

1 designates a covering for a building structure such as the roof or siding thereof usually composed of material adapted to receive shingles or other covering material. 2 designates a sheet of material covering the features of my invention shown to be of substantially diamond shape 35 with its side edges in right angular relation to each other (Fig. 4) adapted to be folded on lines 3, 4, 5 and 6, forming hook side members 7, 8, 9 and 10, the side members 7 and 8 being folded upwardly as shown in Fig. 2 and the side members 9 and 10 being folded downwardly. Fig. 40 3 shows a back view of the shingle with the side members 9 and 10 in folded position. The opposite sides 9 and 10 are slotted as indicated at 11 and 12 and the corners extend slightly outward from the side edges forming nail tabs 13 and 14 having openings 15 and 16 for 45 the nails to fasten the shingles to the structure (Fig. 1). The lower corner of the sheet as shown in Fig. 4 is cut on a line as indicated at 17 whereby the cut line 17 forms the lower end of the side flanges 9 and 10 after being folded on the lines 5 and 6.

50 The centering tab 18 is formed in the sheet, shown in Fig. 6, by folding on the lines 3 and 4, turning the side members 7 and 8 upwardly and inwardly, then folding the side flanges 7 and 8 on lines 19 and 20 inwardly in a parallel relation (Fig. 6) and on fold lines 21 and 22 outwardly, until the tab 18 (Fig. 6) lies flat on the side members 7 and 8 as illustrated at 23, Figs. 1 and 2, and thereby forming a pocketlike joint of the side flanges 7 and 8 on the uppermost corner of the sheet.

The nail tab corners are then folded on lines 24 and 60 25, 26 and 27, and 28 and 29, respectively, and then folded on lines 30 and 31 (Fig. 9) so that the tabs 13 and 14 will lie flat as illustrated in Fig. 2 and the nail tab 13 extending to the right and the nail tab 14 to the left as illustrated in Fig. 2. With this form of folding 65 the base 32 of the nail tabs 13 and 14 will lie on top of the side members 7 and 8, respectively. An alternate form of folding may be accomplished by the illustration in Fig. 5 by first folding the lines 30 and 26 at the same time and line 27 so that the side member 7 will lie over the folded portions 33 and 34 then the tab folded over the edge 35 of the side member 7. This folding might

70

be preferred in some instances as a more simple method of accomplishing such fold.

When the sheet 2 is folded as above described a structure as shown in Figs. 2 and 3 will be ready for application to the roof or siding structure as shown in Fig. 1.

A shingle 36 as thus formed is applied to the roof structure by nails (not shown) through the openings in the nail tabs 13 and 14 with the side hook members 7 and 8 in folded position for receiving the next succeeding sheet 37 by placing the side edge or hook member 9 under the side edge or hook member 7 with the folded nail tab or the folded edge 38 formed on fold line 25 thereof engaging over the member 7 and extending under the folded portion 39 (Fig. 6) or underneath the aligning tab 18 formed on the fold line 19. A sheet 40 with the hook member or side 10 engaging the hook side 8 of the sheet 36 in like manner will be placed on the opposite side of the centering tab or pocket 18 and the covering built up in such a manner so that the tab 18 will be on the top of the structure to cover any open spaces to prevent air and moisture from going through the roof structure. Should any rain blow under the flap 18 the tabs or side hook members on the top shingle will catch the same and it will flow out at the bottom point 41 provided by the folding of the side members 9 and 10 and forming a slot 42 (Fig. 3) when the side members are folded, thus allowing the moisture to flow on top of the next underneath shingle or sheet as at the point 43 (Fig. 1). When the next sheets or shingle members 36 are placed on each side as above described with the centering tab 18 exposed then the succeeding shingle or sheet member may be centered over the center flap 18 by engaging the side members 9 and 10 on the respective sides thereof underneath the side members 7 and 8 of the next lower shingle whereby the slot 42 forming lower edges 44 and 45 of the side members 9 and 10 will also engage along the fold lines 24 and 25 as indicated at 46 and 47 (Fig. 2); thereby providing a rigid interlocking of the shingles and thus the shingle 48 will cover the tab 18 entirely as at 48 and the shingle may be nailed through the nail tabs 13 and 14 as above shown. The shingles are connected as above described until the entire building or roof structure is covered.

In Fig. 10 I have illustrated a slightly different form of my invention whereas the sheet is of substantially diamond shape but whereby the upper and lower angles are greater than the left and right angles of the sheet thus requiring a slightly different fold. In this sheet numbered 50 the sides forming hook members are the same as the invention shown in Fig. 1 and are given like numbers. The fold lines are shown in dotted lines as indicated at 51, 52, 53 and 54, the lines 51 and 52 running parallel to each side edge 55 and 56 to a point as indicated at 57 and 58 and thence outwardly to the side edges 55 and 56 of the sheet as indicated at 59 and 60. The fold lines 53 and 54 run from the notch 61 to the corners 62 and 63 of the sheet and fold lines 64 and 65 intersect at the points 57 and 58 and extend to the side edges 55 and 56 at an angle to lines 59 and 60. Notches 66 and 67 are formed in the lower side edges of the sheet and nail tabs 68 and 69 extend outwardly from the side edges of the sheet. The fold lines 51 and 52 cross each other as indicated at 70 and fold lines 71 and 72 extend from that point outwardly at a right angle to the upper side edges 55 and 56 of the sheet for folding of the centering tab 73.

In folding the sheet as shown in Fig. 10 the sides 9 and 10 are folded downwardly and inwardly on the lines 53 and 54 and the side members 7 and 8 are also folded upwardly and inwardly on the lines 51 and 52. The center tab 73 is formed by folding on the lines 71 and 72 after the side members 7 and 8 are folded as indicated in Fig. 11. It will be seen that the fold lines 51 and 52 from the point 70 to the side edges are bent as indicated at 74, Fig. 11. Before the side member 7 is completely

folded the corner nail tab 68 is formed by bending upon the fold lines 24 and 64. The side member 7 is then bent on lines 51 and 59 upwardly and inwardly to lie over a portion of the sheet. The sheet is then bent on the line 54 from the slot 66 to the corner edge 62 of the sheet and turned outwardly so that the tab 68 will extend outwardly from the side face of the sheet as indicated in Fig. 13. The tab 69 is formed in the same manner as 68 by folding on the lines 25 and 65 and lines 53 and 69, respectively.

The manner of assembling the shingles on the roof or building structure is the same as in the form of invention shown in Fig. 1.

Figs. 14, 15, 16 and 17 show a still further modified form of the invention wherein a sheet of material is substantially in the shape of a parallelogram comprising a sheet of material 75 having side edges 76, 77, 78 and 79 with four fold lines spaced from said side edges as indicated at 80, 81, 82 and 83. The lines 80 and 81 running from the side edges 76 and 77 to a point as indicated at 84 and 85 and there intersecting lines 86 and 87 extending in a right angle from the edges 76 and 77 and then angle to the corner of the sheet as indicated at 88 and 89. Lines 82 and 83 intersect notches 90 and 91 and the lower left hand corner is notched as indicated at 92 forming side or hook members 93 and 94 folded on the lines 82 and 83. The sheet may also be folded on the lines 80 and 81 forming side or hook members 95 and 96 as in the previous forms of the invention. The side members 95 and 96 being turned upwardly and inwardly and the side members 93 and 94 being turned downwardly and inwardly.

The centering tab 73 is formed in this form of the invention by folding of the side members 95 and 96 on the fold lines 80 and 81 and on fold lines 98 and 99, the centering tab being numbered 97 as illustrated in Fig. 15 and the lines 80 and 81 forming the folded edges as indicated at 100, Fig. 15. Corner or nail tabs 101 and 102 are provided by folding on the fold lines 82 and 83 from the notches 90 and 91 to the edge of the sheet and on lines 86, 88 and 24, respectively, of the tab 101, and 87, 89 and 25 of the tab 102 so that the tabs 101 and 102 will lie flat over the hook members 76 and 77 as illustrated in Fig. 17. The folding of the nail tabs being illustrated as best shown in Fig. 16.

In assembling the shingles on a wall structure or roof of a building the hook members engage the respective shingles as illustrated in the form of the invention shown in Figs. 1 to 9, inclusive, and the side edges will form right congruent angles so that the nail tabs will be formed to hook under the centering tab 97 as illustrated in the preferred form of the invention as thus the centering tab will be completely covered to aid in laying the shingles in a straight line and to close the vent between the shingles thus preventing moisture and rain from entering underneath the shingles. With this form of the invention the shingle may be laid along the straight side edges of a roof or building structure so that there need be no cutting of the shingles in placing them on the structure.

It will be obvious from the foregoing that I have provided an improved shingle cut and folded from a single piece of material such as aluminum or other like metal or plastic which would be economical to manufacture and efficient in operation.

What I claim and desire to secure by Letters Patent is:

1. A shingle made from a single sheet of material suitable for roof covering or the like comprising, a body portion having side edges, upturned hooking flanges on two adjacent sides of the shingle body portion, underturned hooking flanges on the other two adjacent sides of the shingle body portion, folded extensions from the adjacent ends of said upturned hooking flanges overlying said adjacent ends of said upturned hooking flanges, a top tab connecting said folded extensions in overlying

relation thereto, and extensions adjacent the remote ends of the upturned hooking flanges folded in overlying relation to said upturned hooking flanges and terminating in nail tabs extending outwardly from the respective side edges of the shingle body portion, the adjacent ends of said undeturned hooking flange terminating in spaced parallel edges lying substantially diagonally of the body portion.

2. A shingle made from a single sheet of material suitable for roof covering or the like comprising a body portion having side edges, upturned hooking flanges on two adjacent sides of the body portion, under turned hooking flanges on the other two adjacent sides of the body portion, folded extensions from the adjacent ends of said upturned hooking flanges defining a centering tab having a top tab and abutting angular bottom tabs defining a pocket, another folded extension extending from each of the remote ends of the upturned hooking flanges in overlying relation to the respective flange and terminating in fold lines diagonal to their respective side edge, a member extending from each of the said diagonal fold lines in overlying relation to said extension and having a fold line in alignment with the inner edge of the respective upturned hooking flange, a nail tab extending from the said fold line of each of the respective members in overlying relation thereto and extending outwardly from the body portion perpendicular to the respective side edge, said nail tabs cooperating with said remote ends of the flanges and body portion of the shingle to define pockets, and one said undeturned hooking flange having an end adjacent an end of the other undeturned hooking flange defining a pocket.

3. A shingle made from a single sheet of material suitable for roof covering or the like comprising, a body portion having side edges, upturned hooking flanges on two adjacent sides of the shingle body portion, undeturned hooking flanges on the other two adjacent sides of the shingle body portion, said upturned hooking flanges each respectively terminating at adjacent ends in fold lines diagonal to the respective side edge of the body portion and terminating at the other end at a second fold line perpendicular to the respective side edge of the body portion, an extension member extending from the first named fold line of one of the upturned hooking flanges in overlying relation to said flange and terminating in a fold line parallel to the side edge of the body portion, an extension member extending from the first named fold line of the other upturned hooking flange in overlying relation to said flange and terminating in a fold line parallel to the side edge of the body portion, a centering tab extending from the end fold lines of the extension members and in overlying relation to said extension member, a member extending from the second named fold line of one of the upturned hooking flanges in overlying relation to said flange and terminating in a fold line diagonal to the side edge of the shingle body portion, a second member extending from the diagonal end fold line of the first named member in overlying relation to said first member and having a fold line in alignment with the inner edge of the upturned hooking flange, a nail tab extending from the fold line of the second member in overlying relation to said second member and extending outwardly from the body portion perpendicular to the respective side edge, a tab extending from the second named fold line of the other upturned hooking flange in overlying relation to said flange and terminating in a fold line diagonal to the side edge of the shingle body portion, a second tab extending from the diagonal end fold line of the first named tab in overlying relation to said first tab and having an end fold line in alignment with

the inner edge of the said upturned hooking flange, and a nail tab extending from the fold line of the second tab in overlying relation to said tab and extending outwardly from the body portion perpendicular to the said side edge.

4. A shingle made from a single sheet of material suitable for roof covering or the like comprising, a body portion having front, rear and side edges, a front hooking flange folded upwardly and inwardly on a fold line and terminating at one end at a second fold line diagonal to the front edge of the body portion and terminating at the other end at a third fold line perpendicularly to said front edge, a side hooking flange folded upwardly and inwardly on a fold line and terminating at the end adjacent the diagonal end of the front flange at a second fold line diagonal to the side edge of the body portion terminating at the other end at a third fold line perpendicular to said side edge, a rear hooking flange folded downwardly and inwardly on a fold line and terminating in ends that are diagonal to the fold line but parallel to each other, a second side hooking flange opposite the first named side hooking flange folded downwardly and inwardly on a fold line and terminating in ends that are diagonal to the said fold line but parallel to each other, an extension member extending from the second named fold line of the front hooking flange in overlying relation to said flange and terminating in a fold line parallel to the front edge of the body portion, an extension member extending from the second named fold line of the first named side hooking flange in overlying relation to said side hooking flange and terminating in a fold line parallel to the side edge of the body portion, said extension members defining a pocket, a centering tab extending from the end fold lines of the extension members and in overlying relation to said extension members whereby the tab covers the extension members, a member extending from the third named fold line of the front hooking flange in overlying relation to said front hooking flange and terminating in a fold line diagonal to the front edge of the body portion, a second member extending from the diagonal end fold line of the first named member in overlying relation to said first member and having a fold line edge adjacent the diagonal end fold line parallel to the front edge of the body portion, a nail tab extending from the fold line edge of the second member in overlying relation to said second member and extending outwardly from the body portion perpendicular to the said front edge, a tab extending from the third named fold line of the upwardly turned side hooking flange in overlying relation to said side hooking flange and terminating in a fold line diagonal to the side edge of the body portion, a second tab extending from the diagonal end fold line of the first named tab in overlying relation to said first tab and having an end fold line adjacent the diagonal end fold line parallel to said side edge, and a nail tab extending from the fold line of the second tab in overlying relation to said tab and extending outwardly from the body portion perpendicular to the said side edge.
